ABSTRACT OF THE DISCLOSURE

The invention relates to a gas-fueled lighter having mechanical ignition means for igniting the fuel consisting of a one-piece operating member covering the top face of the lighter. This operating member controls opening and closing of the burner valve and drives an abrasive wheel for effecting sparks for igniting the flow of fuel thereby causing a flame emerging through an aperture within the operating member.

GAS-FUELED LIGHTER

The invention is concerned with a gas-fueled lighter having mechanical ignition means and a one-piece operating member which is covering the top face of the lighter.

A known lighter of this kind is described in U.S. Patent No. 3,150,509. This lighter is provided with a one-piece operating member which is pivotally hinged in the middle of the lighter's top and which is swinging about one or the other side of this pivot. The operating member of the known lighter has a plane surface at its upper side and protrudes at both ends into the lighter by means of tongues in the shape of a sector.

When operated f.e. at its right end the operating member is turning about its pivot for such amount that its tongue or projection engages a wick tube and is shifting this wick tube together with its wick against the movement of the operating member through a predetermined angle.

The rotation of the abrasive wheel on a flint stone causes ignition. The flame produced thereby is directed upward and sloping to the left. The flame is emerging freely since the operating member has opened a certain aperture.

When the operating member is operated on the left side the function is reversed, e.g. the tongue belonging to the left side is pushing the wick tube to the right. After ignition the flame is emerging through the respective aperture between the operating member and the lighter corpus.

It is a disadvantage of the known lighter that the wick tube must be shifted in order to bring the ignited flame into the direction of the angle of the aperture.

A further disadvantage is the fact, that the operating member is mounted on a separate axis which is provided above the spark-producing mechanism.

Notwithstanding this fact, the known lighter is only suitable for the ignition of a wick and not of a gas, since a burner valve cannot be operated within such arrangement.

One object of the invention is therefore to create a mechanical operable gas-fueled lighter which avoids this disadvantage and provides a simple construction of the operating means whereby the operating member also controls the burner valve from which the gas to be ignited is emerging.

In a gas-fueled lighter having a mechanical ignition and a one-piece operating member which is fully cover-

2

ing the upper face of the lighter one object of the invention is achieved by means of a bearing frame provided with lugs which are carrying an axis, on which are commonly pivoted an operating member and an abrasive wheel. The operating member is provided with a flame exit located opposite to the burner valve and its front edge is provided with a hook-like projection and a slot which is operatively engaging the burner valve. A further feature of the invention is the provision of an abrasive wheel loosely mounted on an axis which is connected with a driving member pivoted on the same axis, a two-piece member provided with pins which are eccentrically (with respect to said axis) engaging into said driving member, said two-piece member is provided at its end opposite to said pins with a roller and a supporting member mounted on a further axis carried by said two-piece member, said supporting member is pivoted at its other end within a bearing frame thereby supporting said two-piece member.

An advantageous feature of the invention is the fact, that the roller is biased into contact with the inner surface of the operating member by means of a tension spring which is engaging, at one end with the bearing frame and at the other end with the common axis of the two-piece member and the supporting member, and thereby holding said operating member in its rest position.

The invention is further characterized in that a bracket is provided, which is fixed to the bearing frame by means of a screw, and which is at one end overlapping the axis of the supporting member by means of a half ear and which is provided at its other end with a projection on which one end of the spring is hooked over.

In the drawings one example of the invention is shown only schematically:

FIG. 1 shows a section of the operating mechanism according to the invention in its rest position.

FIG. 2 shows the same section of the operating mechanism in an operating position, and

FIG. 3 a perspective exploded view of the operating elements without the operating member prior to assembly but positioned for assembly therefor.

The operating mechanism is supported by a tank 1 filled with gas and comprising a flint tube 23. The tank is closed by an upper wall 2. This wall 2 is connected to the bearing frame 4 by means of a screw 3. The bearing frame 4 is provided with two upwardly projecting lugs 5 which are bearing the pivot pin 6 for the abrasive wheel or sparking 7 and the operating member 8.

The operating member 8 is provided at one end with a flame aperture 9 and an inwardly projecting flange 10, which in turn is provided with a slot 11, which is engaging the burner nozzle and controls the burner valve when the member 8 is operated.

The bearing frame 4 is provided with a bracket 14 for bearing a support lever 18, the bracket being fixed to said frame by means of screw 3. The screw 3 is screwed into a threaded bush 24 within the bearing frame 4. One end of the bracket 14 is overlapping the axis 17 of the lever 18 by means of a half ear 16. The bearing frame 14 is provided at its other end with a projection 15 upon which one end of the spring 22 is hooked.

At the free end of the supporting lever 18 there are mounted one or more rollers by means of a pin 20. The other end of spring 22 is hooked over the pin 20. The spring 22 is biasing the roller 19 into contact with the inner surface of the operating member 8. At lever 21 is rotatably mounted with one end on pin and its other end is engaging a driving member 25 by means of lugs 6' (FIG. 3).

The lever 21 is preferably of two parallel members

which are connected together by means of a screw 28 and straddle member 25.

The driving member 25 is also mounted on pivot pin 5 and surrounds the abrasive wheel 7 on said common pin. The abrasive wheel is provided with a click-stop or ratchet teeth arrangement 27 engaged by a springy pawl 6. This arrangement operates as a ratchet device to prevent the engagement in more than one direction of rotation of the abrasive wheel 7.

The lugs 6' on double lever 21 engage holes 30 which are eccentric with reference to holes 31 for pivot pin 10. The filling valve preferably located at the bottom of the tank 1 and a casing surrounding said tank are not shown. The casing usually covers the entire mechanism of the lighter and is open only at its top to an extent such that the operating member 8 is movable through 15 a distance sufficient to perform its functions. The casing when placed in position covers all the space between the operating member and the tank.

OPERATION

In order to operate the lighter the member 8 is depressed at its right end. The roller 19 thereby moves along the inner surface of the member 8 toward its right end. As a result, support lever 18 swings about its pivot 17. Simultaneously the spring 22 is biased.

The lever 21 is moving in the direction of the roller 9 and rotates the driving member 15, thereby rotating the abrasive wheel.

When swinging the operating member 8 about pin 6 he flange 10 is also swung upwardly thereby causing opening of the burner valve 13 and gaseous fuel is streaming out of the burner nozzle 12.

The gaseous fuel is ignited by the simultaneous operation of the spark producing mechanism. The flame produced in that manner is emerging from the aperture 9 within the operating member 8.

Upon releasing of the operating pressure on the right end of the member 8, the spring 22 draws the operating member 8 into its initial position as shown in FIG. 1 by means of the roller 19, thereby swinging the lever 8 around its pivot 17.

Simultaneously the lever 21 is moving forward and hereby rotating the driving member 25 counterclockwise around its pin 6 by means of lugs 6'.

The flange 10 of the operating member 8 swings down. Thereby the shanks defining the slot 11 are coming in contact with a bearing surface provided at the burner nozzle 12, pressing down this nozzle and closing the burner valve 13.

What is claimed is:

1. A gas-fueled lighter with a fuel-supplying and fuel-igniting mechanism, said mechanism comprising in combination:

a mounting frame;
a pivot pin supported on said frame;
a fuel valve for releasing a flow of gaseous fluid in an open position and biased into a closed position;
an operating member pivotally supported at one end on said pin for pivoting said member between a rest position covering said mechanism and an oper-

ating position, said operating member being biased into its rest position and movable into its operating position by pressure applied thereto, and said operating member having an opening for the passage of a flame upon ignition of released fuel and actuating portion engaging said fuel valve to open the same upon pivoting of the operating member into its operating position;
a sparking wheel rotatably supported on said pivot pin; and
coupling means coupling the sparking wheel to the operating member to rotate said wheel for generating sparks igniting fuel escaping from the valve upon movement of the operating member into its operating position,
said coupling means including a driving member rotatably supported on said pivot pin, one-way transmission means coupling said driving member to said wheel, a coupling link hinged at one end to said driving member at a point thereof eccentric with reference to the rotational axis of said pin; and
a support link hinged at one end to the other end of the coupling link and at the other end to said mounting frame, said links being biased into pressure engagement with the operating member in any pivotal position of the latter, movement of the operating member into its operating position effecting displacement of the coupling link in lengthwise direction and thus rotation of the sparking wheel.

2. The lighter according to claim 1 wherein said transmission means comprise ratchet teeth on the sparking wheel and a pawl member coacting with said teeth and rotatably supported on said pivot pin, said pawl member being attached to said driving member for rotation in unison therewith thereby effecting said rotation of the wheel.

3. The lighter according to claim 1 wherein said coupling link has two parallel branches straddling said driving member and mounting lugs eccentrically engaging the driving member for rotation thereof upon displacement of the coupling link in lengthwise direction.

4. The lighter according to claim 1 wherein said one end of the support link and said other end of the coupling link are pivotal on a common second pivot pin, a roller is rotatable on said second pin, and a spring biases said roller against said operating member to urge the same toward its rest position.

5. The lighter according to claim 4 wherein a support bracket is secured to said mounting frame, said bracket defining a bearing for said other end of the support link and also defining a hook portion retaining one end of said spring, the other end of the spring being attached to said second pivot pin.
